SAMUEL BROWN, OF PHILADELPHIA, PENNSYLVANIA, ASSIGNOR
TO HIMSELF AND C. R. CARVER, OF THE SAME PLACE.

Letters Patent No. 85,064, dated December 22, 1868.

IMPROVEMENT IN FEED-ATTACHMENT FOR MACHINERY.

The Schedule referred to in these Letters Patent and making part of the same.

To all whom it may concern:

Be it known that I, SAMUEL BROWN, of Philadelphia, in the county of Philadelphia, and State of Pennsylvania, have invented a new and improved Feed-Attachment for Machines; and I do hereby declare that the following is a full, clear, and exact description thereof, which will enable those skilled in the art to make and use the same, reference being had to the accompanying drawings, forming part of this specification, in which—

Figure 1 is a sectional elevation of my invention, the section being taken through the line $z z$ of fig. 2.

Figure 2 is a top view of a part of the feed-mechanism.

Figure 3 is a detail view of the cam, finger-plate, and cam-plates.

Similar letters of reference indicate corresponding parts.

The object of this invention is to provide an improved motion of the fingers of the feed-attachment for rotary cutters for cutting paper, pasteboard, sheet-metal, India rubber, &c., whereby the said fingers are actuated to move forward, in feeding the material to the machine, in a horizontal manner; and at the completion of the forward movement withdraw below the surface of the feed-board or apron, and return beneath the said board, to again rise and repeat the feeding-movement, thus leaving room (during their backward movement beneath the feed-board) to place on the apron the succeeding quantity of material which is to be fed up to the operating-mechanism of the machine.

In the drawings—

C C C is the general frame of a machine, taken to illustrate my feed-attachment.

The said machine has a cutter-roller, A, and counter-roller, B, on each end of which a belt, I, runs, thus receiving motion to drive the feed-attachment.

E is the feed-board or apron, affixed to the extensions G of the frame C C C.

D are plates, between the extensions G, and affixed underneath the apron E.

These plates furnish bearings for the shafts of the feed-mechanism.

The belts I run on pulleys, H, on the short shafts a, the said pulleys being between the plates D and the extensions G.

The shafts a extend through the plates D, and their inner ends are provided with cranks, d.

The said cranks are connected by a rod, b, on which the connecting-rods, f, work loosely, as the cranks revolve.

The opposite ends of the rods f are affixed on a rod, e, the ends of which latter are reduced, and work freely in steps or sockets in the sliding uprights g.

These uprights are provided with projections, p, which slide with easy contact in grooves, o, in the plates D, as shown.

By this train of mechanism, the uprights g are moved to and fro, as the roller B is turned.

The feed-fingers i project up through slots, k, in the feed-board E.

These fingers rise from a finger-plate, m, each end of which is affixed to a vibrating guide-plate, h, which latter is pivoted to the uprights g, as shown.

The lower edge of each guide-plate rests on a cam, n, on the shaft a, (see fig. 3,) and the said cam is so arranged, with reference to the to-and-fro movement of the guide-plate, that it will be uppermost when the guide-plate is moving toward the cutter-roller A, and underneath when the same is receding from the said roller, so that the fingers i will be protruded upward through the slots, just as they begin to move forward, and so held until the forward movement is completed, when the cam, having then passed from contact with the guide-plate h, permits the latter to rest on the shaft a, or reduced part of the cam, and the guide-plate thus withdraws the fingers from the slots.

The shaft a then supports the guide-plate during the backward stroke, when the cam n again encounters the guide-plate, and raises it, as before.

Whatever is laid on the feed-board, in front of the fingers, (as shown in red color,) will thus be actuated up to the cutter-roller, or other prehensive part of the mechanism of a machine to which my invention is attached; but in order to obviate the necessity of adjusting the material to be fed up by the fingers, against the latter, I employ a guide-board, g, having slots which merge into the slots of the apron, as shown.

The material is placed against this guide-board while the fingers are passing backward underneath the apron, and the fingers, in rising, emerge from the slots behind the material placed against the guide-board.

By means of this feature, no especial care is necessary in placing the material upon the apron, but the same may be expeditiously laid on as fast as the fingers feed it up.

Having thus described my invention,

What I claim as new, and desire to secure by Letters Patent, is—

1. The combination of the finger-plate m, guide-plate h, upright g, projection p, grooved plate D, shaft e, connecting-rod f, rod b, crank d, and cam-shaft a, all arranged to operate as herein described, for the purpose specified.

2. The guide-board g, substantially as described, in combination with the apron E, fingers i, and their actuating-mechanism, all substantially as described, for the purpose set forth.

3. The guide-plate h, carrying the fingers i, operated, as described, by the cam n, upon the shaft a, through the medium of the crank d, connecting-rod f, shaft e, and upright g, sliding in the grooved plate D, as herein described, for the purpose specified.

SAMUEL BROWN.
